P. E. Hummell,

Scouring and Setting Leather,

No 17,576.

Patented June 16, 1857.

UNITED STATES PATENT OFFICE.

PETER E. HUMMEL, OF PULASKI, NEW YORK.

MACHINE FOR SCOURING AND SETTING LEATHER.

Specification forming part of Letters Patent No. 17,576, dated June 16, 1857; Reissued March 19, 1867, No. 2,518.

To all whom it may concern:

Be it known that I, PETER E. HUMMEL, of Pulaski, in the county of Oswego and State of New York, have invented a new 5 and useful Machine for Scouring and Setting Leather; and I do hereby declare that the following is a full, clear, and exact description of the same, reference being had to the annexed drawings, making a part of 10 this specification, in which—

Figure 1, is a side view of my improvement. Fig. 2, is a transverse section of the reciprocating head and guide bars; *x, x*, Fig. 1, indicates the plane of section.

15 Similar letters of reference indicate corresponding parts in the two figures.

My invention consists in the employment or use of a reciprocating head provided with tool stocks and used in connection with a rotating table, the parts being arranged as will be hereinafter fully shown and described whereby the process of "scouring" and "setting" or "extending" leather, hitherto performed by hand, may 20 be accomplished in an expeditious and perfect manner.

To enable those skilled in the art to make and use my invention, I will proceed to describe its construction and operation.

30 A represents a rectangular frame in the upper part of which four pendent rods (*a*) are secured. To the lower ends of these rods guides bars (*b*) (*b*) are attached, the two guides being parallel with each other 35 and having a plate B fitted between them, the sides of said plate being provided each with a groove in which the guide bars (*b*) are fitted.

To the under side of the plate B and at 40 each side a pendent frame (*c*) is secured, and the ends of two shafts (*d*) (*d*) are fitted in their frames (*c*), the ends of the shafts (*d*) being fitted in bearings (*e*) which are placed in vertical slots (*f*) in 45 the frames, and have spiral springs (*g*) bearing on their upper edges, said springs being placed around vertical guide rods or pins (*h*) attached to the bearings. The upper ends of the springs (*g*) have plates (*i*) placed upon them, and screws (*j*) which pass through the plate B rest or bear 50 upon said plates (*i*), the springs (*g*) being more or less compressed and their pressure

upon the bearings (*e*) graduated as desired by turning the screws (*j*). 55

The shafts (*d*) (*d*) are allowed to turn freely in their bearings and a socket (*k*) is attached to each shaft (*d*). These sockets (*k*) extend the whole length of the shafts and the tools (*l*) are fitted within 60 them. These tools are constructed of the usual material, stone or metal, and of the usual flat rectangular form, the corners being rounded to prevent injury to the leather. 65

The shafts (*d*) (*d*) have each a rod (*m*) projecting radially from them. These rods (*m*) have screw threads cut on them, and weights (*n*) are fitted thereon, said weights by being turned may be brought nearer to 70 or farther from the shafts (*d*) (*d*), so that the tools may be counterpoised and their weight or pressure graduated as may be desired. The shafts (*d*), are also allowed to yield or give in consequence of being fitted 75 in the yielding or sliding bearings (*e*).

A reciprocating motion is given the plate B by means of a connecting rod C and crank D attached to a driving shaft E.

F is a vertical arbor or shaft which is 80 permanently secured to the center of the base G of the frame A. On this arbor or shaft a revolving table or bed H is placed, the upper end of the arbor or shaft fitting in a socket (*f*) which is secured to the 85 under side of the bed. A collar (*g'*) which is secured to rods (*h'*), attached to the under side of the bed, fits on the arbor or shaft F. The bed is allowed to turn freely on the arbor or shaft F, and the 90 leather I to be operated upon is stretched out upon the bed H. A reciprocating motion is then given the plate B and consequently the tools (*l*), by turning the driving shaft E, and the leather is presented to 95 the action of the tools so that all parts will be properly acted upon by turning the bed H.

By means of this machine leather may be "scoured" and "set" or "extended" much 100 more expeditiously than by the hand process. The tools are allowed to yield or give and their pressure may be graduated with the greatest facility, and the work performed in a perfect manner.

Having thus described my invention,

what I claim as new, and desire to secure by Letters Patent, is:

The revolving table or bed H, in combination with the reciprocating head formed 5 of the plate B, having the frames (a) attached, in which the shafts (d), (d), are fitted, the shafts being provided with sock-

ets (k), and adjustable counterpoises (a); substantially as herein shown and described, and for the purpose set forth.

PETER E. HUMMEL.
